F. HARDINGE,
METHOD OF AND APPARATUS FOR LINING FURNACE FIREBOXES,
APPLICATION FILED SEPT. 20, 1920.

1,393,777.

Patented Oct. 18, 1921.

UNITED STATES PATENT OFFICE.

FRANKLIN HARDINGE, OF CHICAGO, ILLINOIS, ASSIGNOR TO HARDINGE BROTHERS, INC., OF CHICAGO, ILLINOIS, A CORPORATION OF ILLINOIS.

METHOD OF AND APPARATUS FOR LINING FURNACE-FIREBOXES.

1,393,777.

Specification of Letters Patent.

Patented Oct. 18, 1921.

Application filed September 20, 1920. Serial No. 411,414.

To all whom it may concern:

Be it known that I, FRANKLIN HARDINGE, a citizen of the United States, and resident of Chicago, in the county of Cook and State 5 of Illinois, have invented a certain new and useful Improvement in Method of and Apparatus for Lining Furnace-Fireboxes, of which the following is a full, clear, concise, and exact description, reference being had 10 to the accompanying drawings, forming a part of this specification.

My invention relates to improvements in an apparatus for, and method of, constructing the bed of the fire box of furnaces and 15 more particularly furnaces using oil burners of the type described and claimed in my co-pending application, Serial No. 380,794, filed May 12, 1920, wherein a rotary spindle is arranged to rotate an atomizing nozzle operating in the fire box.

The principal object of my present invention resides in the provision of an apparatus of the character described, which is simple in construction, and easily manipulated, 25 and whereby an unskilled workman may quickly build the fire box bed of a furnace absolutely true and concentric with respect to the rotary spindle and atomizing nozzle adapted to operate in the fire box.

30 The foregoing and other objects of my invention will be apparent from a consideration of the following detailed description taken in connection with the accompanying drawings, wherein—

35 Figure 1 is a vertical section of a furnace fire box illustrating the rotary spindle of an oil burner located therebeneath on which my improved apparatus is mounted, in co-acting relation, for constructing the bed of 40 the furnace fire box, and

Fig. 2 is a plan view of Fig. 1, certain portions of the fire box bed being broken away to disclose more clearly the details of the supporting structure therebeneath.

45 The same reference numerals designate the same parts in the two views.

Referring to the drawing, the reference numeral 5 designates the furnace fire box, which is preferably of metal and conformed 50 to provide an annular rib 6. Supported upon the rib 6 are the metal cross bars 7 and 8, to which are bolted on the nether side the angle iron supports 9—9. A hollow, conical ring 10, which in operation surrounds the 55 burner, as described in my co-pending ap-

plication, above mentioned, is provided with a plurality of laterally projecting lugs 11, which rest upon the angle iron support 9, and are vertically adjustable thereon by means of adjusting screws 12. The ring 10 is provided adjacent its upper edge with an annular shoulder 13 for supporting an air vane ring, not shown, but described in my aforementioned application. The screws 12 are so adjusted as to bring the air vane ring 60 into proper relation with the air vanes provided on the atomizing nozzle illustrated in my aforesaid co-pending application. The lower edge of the ring 10 is turned outwardly and upwardly as at 14 to provide an 65 annular trough 15 in which a suitable drain hole 16 is provided. A pipe may be threaded into the hole 16 for draining the trough 15. A ring 17, supported by the cross bars 7 and 8, in turn supports a plurality of sheet 70 metal sectors 18 which have overlapping, interlocking edges 19. The inner ends of the sectors 18 rest upon the upturned edge of the ring 10 and at their outer ends are supported by the ring 17, at such an elevation 75 that the sheet metal ring formed by the sectors 18 inclines downwardly toward the center of the fire box as illustrated. The outer ends of the sectors 18 are preferably flanged upwardly as shown at 20. Fire bricks 21 are 80 arranged in a circle around the vertical sides of the fire box 5 and are supported at their lower ends by the sectors 18.

Having described the details of the fire box and the fire box bed supporting structure, I will now proceed to a detailed description of the apparatus which I propose providing for constructing the fire box bed and conforming the upper surface thereof.

Illustrated at 22 is the rotary spindle 95 which, during operation of the furnace, as described in my aforesaid co-pending application, is adapted to rotate an atomizing nozzle. The means for driving the spindle 22 is conveniently located in the housing 100 23 which is carried upon a base plate 24. The base plate 24 is slidably mounted upon the bed plate 25, which comprises the longitudinally extending rails 26 and 27, the former of which is flat on its upper surface, 105 and the other of which is in the form of an inverted V rail. By this means, the base plate 24 is movable longitudinally of the bed plate 25 to position the spindle 22 as desired. Mounted upon the spindle 22, and 110

having screw threaded relation therewith, is a member 28, which is provided with a plurality of radially extending arms 29, the outer ends of which are machined, as at 30, 5 on a circumference having the axis of the spindle 22 as a center. The portion 30 is so machined as to provide a horizontal finished surface 30^a, whereby the ring 10 may be properly positioned vertically with respect to the fire box; the vertical finished surface 30^b serving to position the ring centrally, relative to the fire box. The surfaces, being machined very accurately, insure against maladjustment of the ring relative to the spindle.

The member 28 is centrally bored as at 32 to provide a bearing for a pin 33 extending downwardly from the inner end of a sweep 34. The sweep 34 is suitably conformed on 20 its lower and outer edges to the desired contour and is provided with a handle 35, adjacent its outer end, whereby it may be swung around in a horizontal plane on the pin 33.

In constructing the bed of the furnace fire box, the supporting structure, comprising the cross bars and angle iron supports, is placed in position upon the annular rib 6, the spindle 22 is then brought into position at approximately the center of the fire box 30 beneath the supporting structure, the base plate 24 being moved along the bed plate 25 on the rails 26 and 27, and being suitably permanently secured in position. The member 28 is then fixed upon the spindle 22 by 35 threading the same thereon, or, if desired, the spindle may be driven slowly from the drive shaft to screw the same into the member 28. The ring 10 is then placed upon the member 28, so that the lugs 31 rest upon the shoulders 30. The screws 12 are then 40 adjusted properly to level the ring 10. When the screws 12 are so adjusted that the ring is level and true with respect to the member 28 and spindle 22 it will not be necessary to further adjust these screws to 45 properly position the air vane ring, above mentioned, with respect to the rings of the atomizing nozzle, because the shoulders 30 of the member 28 are very accurately machined to avoid the necessity for this.

After the ring 10 is properly positioned, the ring 17 is then placed upon the cross bars 7 and 8, and the sectors 18 placed thereupon. The fire bricks 21 may then be placed 55 and cemented in position, whereupon the space between the lower ends of the fire bricks and the ring 10 may be filled in with plastic fire clay, and conformed as shown at 36 by means of the sweep 34, which may 60 be swung around in a horizontal plane on the pin 33, by means of the handle 35. It will be apparent that the above operations may be easily accomplished by an unskilled workman, and require little time.

65 After the fire box bed has been completed,

the sweep 34 is removed by lifting the same out. The member 28 is then turned slightly, so that the outer ends of the arms 29 do not lie beneath the lugs 31 of the ring 10. The member 28 is then removable by simply 70 holding the same and driving the spindle 22 in a direction opposite that in which it is driven when the member 28 is mounted upon the spindle. The member 28 is then removable by lifting the same out. The air 75 vane ring may then be placed in position on the shoulder 13 of the ring 10, and the atomizing nozzle screwed upon the spindle in operating position in place of the member 28.

80 While I have described the details of the preferred embodiment of my invention, it is to be clearly understood that my invention is not limited to these details, but is capable of other adaptations and modifications within the spirit and scope of the appended claims.

What I claim is:

1. The combination with a machine for burning fuel oil, comprising a rotary spindle 90 for rotating an atomizing nozzle, of means for co-acting with said spindle in forming the bed of the fire box of the furnace in which said atomizing nozzle is to operate, comprising a member having screw threaded engagement with said spindle and provided with a plurality of arms for supporting a ring forming a part of said fire box bed, and a sweep, for conforming the upper surface of the fire box bed, rotatably mounted on 100 said member.

2. The combination with a machine for burning fuel oil, comprising a rotary spindle for rotating an atomizing nozzle, of means for co-acting with said spindle in 105 forming the bed of the fire box of the furnace in which said atomizing nozzle is to operate, comprising a member having screw threaded engagement with said spindle and provided with a plurality of arms for supporting a ring forming a part of said fire 110 box bed.

3. The combination with a machine for burning fuel oil, comprising a rotary spindle for rotating an atomizing nozzle, of means 115 for co-acting with said spindle in forming the bed of the fire box of the furnace in which said atomizing nozzle is to operate, comprising a member having screw threaded engagement with said spindle, and a sweep 120 for conforming the upper surface of said fire box bed rotatably mounted on said member.

4. The combination with a machine for burning fuel oil, comprising a rotary spindle 125 for rotating an atomizing nozzle, of means for co-acting with said spindle in forming the bed of the fire box of the furnace in which said atomizing nozzle is to operate, comprising a member having screw thread- 130

ed engagement with said spindle, and means for supporting a ring forming a part of said fire box bed.

5. The combination with a machine for burning fuel oil, comprising a rotary spindle for rotating an atomizing nozzle, of means for co-acting with said spindle in forming the bed of the fire box of the furnace in which said atomizing nozzle is to operate, 10 and a sweep rotatably mounted on said spindle for conforming the upper surface of the bed of said fire box.

6. The combination with a machine for burning oil, comprising a rotary spindle for 15 rotating an atomizing nozzle, of means co-acting with said spindle for positioning a ring forming a part of the bed of the fire box of a furnace, comprising a member having screw threaded engagement with the upper end of said spindle and provided with a 20 plurality of arms for supporting said ring.

7. The combination with a machine for burning oil comprising a rotary spindle for rotating an atomizing nozzle, of means co-25 acting with said spindle for positioning a ring forming a part of the bed of the fire box of a furnace, comprising a member having screw threaded engagement with the upper end of said spindle and provided with a 30 plurality of arms for supporting said ring, said member being centrally bored to provide a bearing for a sweep for conforming the upper surface of said fire box bed.

8. The method of constructing the bed of 35 the fire box of a furnace, which consists in placing a part of the furnace oil burner beneath said fire box with which the fire-box

bed is to be constructed concentric, positioning a ring forming a part of said fire box bed concentric relative to said part, filling 40 in plastic fire clay around said ring, mounting a sweep on said part and rotating said sweep to conform the upper surface of the clay to form the bed of said fire box.

9. The method of constructing the bed of 45 the fire box of a furnace, which consists in placing a part of the furnace oil burner beneath the fire box with which the fire-box bed is to be constructed concentric, mounting 50 on said part a member provided with a plurality of arms, placing a ring on said member to form a part of the fire box bed, filling in plastic fire clay around said ring and conforming the upper surface of said fire clay to form the bed of said fire box. 55

10. The method of constructing the bed of the fire box of a furnace, which consists in placing a part of the furnace oil burner beneath said fire box with which the fire-box is to be constructed concentric, mounting 60 thereon a member comprising supporting arms, placing a ring on said supporting arms to form a part of the fire box bed, filling in plastic fire clay around said ring, mounting a sweep in said ring supporting member, 65 and rotating said sweep to conform the upper surface of said fire box bed.

In witness whereof, I hereunto subscribe my name this 14th day of September, 1920.

FRANKLIN HARDINGE.
